(57) **CLAIM**

The ornamental design for a motor vehicle and/or toy replica thereof, as shown and described.

DESCRIPTION

FIG. 1 is a front right perspective view of a motor vehicle and/or toy replica thereof showing my new design;

FIG. 2 is a front left perspective view thereof;

FIG. 3 is a rear right perspective view thereof;

FIG. 4 is a rear left perspective view thereof;

FIG. 5 is a front view thereof;

FIG. 6 is a rear view thereof;

FIG. 7 is a top view thereof;

FIG. 8 is a right side view thereof; and,

FIG. 9 is a left side view thereof.

The dashed broken lines form no part of the claimed design and the lightened areas outside the dashed broken lines form no part of the claimed design.
